UNITED STATES PATENT OFFICE.

WILLIAM A. BRAUER, OF NORTH TONAWANDA, NEW YORK.

DRIVING AND CONTROLLING DEVICE.

936,298.

Specification of Letters Patent.

Patented Oct. 12, 1909.

Application filed September 11, 1908. Serial No. 452,638.

To all whom it may concern:

Be it known that I, WILLIAM A. BRAUER, a citizen of the United States, residing at North Tonawanda, county of Niagara, and 5 State of New York, have invented certain new and useful Improvements in Combined Driving and Controlling Devices for Mechanically - Operated Musical Instruments, of which the following is a specification.

10 This invention relates to combined driving and controlling devices for mechanically operated musical instruments.

In mechanically operated musical instruments it is desirable to provide means where- 15 by the tempo may be rapidly and easily changed as desired, as well as safety in operation being insured.

The present invention seeks to provide means to accomplish the foregoing purposes 20 and has for its object the provision of a combined driving and controlling mechanism for mechanically operated musical instruments, whereby the speed may be rapidly and easily varied at will and in which provision will be 25 made for an automatic relief so that if any foreign substance interferes with the action of the instrument, no damage will result.

The invention is carried out by the provision of a friction driving mechanism of 30 novel construction, wherein the relative arrangement of the friction wheels may be rapidly and easily changed and in which the tension of the frictional contact of said wheels may be regulated so that there will be 35 a relative automatic slip thereof if any foreign substance interferes with the action of the machine so that no damage will result, although the tension will be such that under ordinary conditions the instrument will be 40 operated.

The invention is set forth fully hereinafter and its novel features are recited in the appended claims.

In the accompanying drawings:—Figure 1 45 is an elevation, partly in section, of my invention as it appears connected with an electrical motor; Fig. 2, a transverse section taken on the line 2—2 of Fig. 1, looking in the direction of the arrow; and Fig. 3, a 50 plan view of Fig. 2.

Journalized in suitable bearings 1 is a shaft 2 carrying a step pulley 3 which is designed to be belted to the operative parts of the mechanically operated musical instrument. 55 Screwed into the outermost bearing 1 are the

screws 4 which pass through a yoke 5. Slid- 60 able through the yoke 5 is a tension rod 6 surrounded by a coil spring 7, which bears against the yoke, said tension rod having a head 8 against which the other end of the 65 spring bears and being provided with an end-piece 9 of brass, fiber, or other suitable material, which is of suitable size to be re- 70 ceived in the shaft bearing and which bears against the end of the shaft 2. The screws 4 afford means for adjusting the tension of the 75 spring and its consequent pressure on the shaft 2, whereby the force with which the said shaft is urged may be regulated. Secured to the shaft 2 is a friction disk 10.

A suitable electrical motor 11 constitutes the motive power, to the shaft of which there is coupled a shaft 12 which is mounted in a bearing 13. The shaft has a key-way or slot 14. Slidably mounted on the shaft 75 12 is a friction pinion composed of an integral hub and plate 15, a clamping plate 15^a, a wheel 15^b of rubber or other suitable material, such as fiber or wood pulp and screws 15^c by which the wheel 15^b and plates 80 are secured together. Secured to the hub by a lug 16^a is a spline or key 16 which is received in the slot 14, whereby said pinion may slide lengthwise of said shaft but will 85 always rotate with it. The spring 7 holds 85 the friction wheel in the desired frictional engagement with the pinion. By adjusting the tension of the spring, the frictional engagement of the frictional wheel can be 90 regulated at will so that the musical instrument will be operated under ordinary circumstances, but should any interference with its action take place, the relative slip of the friction wheels will prevent any damage 95 being done. Slidable on the shaft 12 is a 95 boxing 17, between whose arms the pinion is disposed. An adjusting shaft 18, which is provided with a hand-wheel 19, is journaled in the bearing 13, and another bearing 20 which is incapable of lengthwise 100 movement, has a screw-threaded part 21, which is threaded through a depending part of the boxing 17 so that on turning said adjusting shaft, the pinion may be shifted crosswise of the friction wheel, and conse- 105 quently, any desired speed obtained. As the bearings wear there is necessarily more or less of a wavering motion of the disk and pinion which, however, is effectually and automatically taken up by the spring 7.

110

Having thus described my invention, what I claim as new and desire to secure by Letters Patent, is:—

1. In a combined driving and controlling device, the combination with a driven shaft, of a friction disk carried thereby, adjusting screws, a yoke adjustable by said screws, a tension rod slidable through the yoke and having its end bearing against the end of the driven shaft, a coil spring surrounding said tension rod which bears on the yoke and on the said rod to hold it in engagement with the driven shaft, a driving shaft, and a friction wheel carried by the driving shaft, which is in engagement with the friction disk aforesaid.
2. In a combined driving and controlling device, the combination with shaft bearings, of a driven shaft mounted in said bearings,

a friction disk carried by said shaft, adjusting screws engaged with one of the bearings, a yoke engaged by said screws, a tension rod which is guided by the yoke and has an end part received in said bearing and abutting the end of the driven shaft, a coil spring surrounding said tension rod and engaged therewith and with the yoke to hold the rod in abutment with the driven shaft, a driving shaft, and a friction wheel carried by said driving shaft which is in engagement with the friction disk.

In testimony whereof, I hereunto affix my signature in presence of two witnesses.

WILLIAM A. BRAUER.
